ABSTRACT OF THE DISCLOSURE

In a process for the fabrication of metal products by stamping out blanks made in a strip of metal and final forming, there are provided the steps of stamping out a rough-shaping in the form of a cup, separating the rough-shaping from the strip, re-introducing said rough-shaping into its former place in the strip where it is maintained and executing on said maintained rough-shaping the final forming operations and expelling the finished product.

The invention relates to a process for the fabrication of metal products from blanks made in a strip of metal.

The fabrication of certain hollow metal products such as, for example, hollow bodies provided with an expanded portion are at present made on two separate machines. Initially, in a first machine, there is formed, in a strip of metal, blanks which are directly submitted to stamping to constitute cups which are detached from the rest of the strip; these cups are then taken up again, one by one, by pliers and transferred to a second machine which executes in a known manner a localised enlargement with the help of a die with a widened tip constituted of several parts.

This method of fabrication has two important disadvantages which, by slowing down the production, diminish the yield and increase the cost price: this known method requires two separate machines, one for the stamping and cutting, and the other for the enlargement of the cup; on this second machine the cups are treated one by one and are manipulated by transfer pliers.

According to the invention, there is provided a process for the fabrication of metal products by stamping out blanks made in a strip of metal and final forming, the process comprising the steps of stamping out a rough-shaping in the form of a cup, separating the rough-shaping from the strip, re-introducing the rough-shaping into the space which it occupied in the strip so that the rough-shaping is held by the strip, executing the final forming operations on the rough-shaping thus held by the strip, and expelling the finished product.

In accordance with a preferred feature the rough-shaping formed is separated from the strip by the action of a die which introduces it into a cutting matrix against the action of a support submitted to the permanent thrust of a spring which pushes the said rough-shaping back into the strip as soon as the die is retracted; because of this the part constituting the waste of the strip is used to hold the rough-shaping which is re-introduced into it after separation and can thus undergo the subsequent operations as if it were gripped in transfer pliers.

The invention will be further described with reference to the accompanying drawings, which illustrate applications of the invention, given only by way of example.

FIGS. 1 to 5 are schematic sectional views of the various phases of fabrication of a hollow component provided with a peripheral enlargement near the base;

FIGS. 6 and 7 are schematic sectional views of two

2

phases of fabrication of a hollow component provided with an elastic component; and

FIGS. 8 and 9 are similar views relating to the fabrication of a hollow rivet.

5 All these schematic figures show only the phases which are useful to the comprehension of the invention, the others having been omitted.

With the help of a press of known type, not described here, there is first made in a strip of sheet metal 2 a series of circular blanks from which, after having made the strip advance by one pass, there are then stamped out a series of rough-shapings in the form of cups such as 1 (FIG. 1) which are still attached to the rest of the strip 2. In the following phase, and after having advanced the strip 2 by another pass, the cup 1 is separated by cutting according to its external diameter; in order to do this, a die 3 pushes down the cup 1 lodged in the cutting matrix 4, on a sliding support 5 subjected to the permanent thrust of a spring 6 (FIG. 2). As soon as it has arrived 15 at the bottom of the course towards the base against the action of the spring 6, the cup is pushed back upwards in such a manner that the cup 1 which has just been separated is re-introduced into the strip 2 at the same part of the blank from which it has been obtained; the strip 2 20 is held in position by a blank press 13 held by springs 14, and the cup is held in place by the rest of the strip (FIG. 3).

After this phase, in the course of which the cutting-off of the cup and its re-introduction into the strip is effected, 30 the strip is once more advanced by a pass to bring the cup, still held in the strip, under a hollow die with a widened tip, in several parts, of a known type (FIG. 4); in the course of this phase the cup is deformed near its base 1a where there is formed a peripheral swelling 1b; 35 after this operation, the strip 2 is advanced by another pass with the cup 1, which has just been provided with the swelling 1b and which is still held gripped by the strip, and a sliding finger is dropped to disengage it from the strip in such a manner that it is freed and can be led 40 towards its final destination.

It should be noted that the process described above allows for the execution of all the various operations necessary for the fabrication of enlarged hollow bodies on a single machine from metal strips which can comprise, next to each other, several rows of blanks at the start, and at the end of the operations several rows of finished bodies.

The process can be applied to the fabrication of other bodies like encased pieces or press-studs.

On a known machine and in accordance with the process which has just been described, there are fabricated, from a strip 9 of sheet metal, cups such as the one referenced 8 in FIG. 6, the cup 8 being reintroduced into 55 the strip 9. The three first fabrication phases of a press-stud are identical with the phases described with reference to FIGS. 1, 2, 3; however, it should be noted that the cup 8 is not as tall as the cup 1 and its bottom has a projection 8a.

60 The cup 8 having been formed and having been reintroduced into the remainder of the strip 9 in the manner explained above, there is lodged in it an elastically deformable metal ring 10 (FIG. 6) forming a spring; encasement is then proceeded with by folding down on the ring 10 (FIG. 7) the edge of the cup 8, still held in the strip 9 which then advances by another pass to allow the ejection of the finished piece by a finger (not shown). In this case, the ring forming the spring 10 is fabricated 65 separately on a special machine but its assembly with the cup is made on the machine on which this cup is fabricated.

By a similar process there can also be fabricated eyelets or tubular rivets obtained by the assembly of a ring forming the head with a piece forming the body. On a first machine, the body 11 is fabricated and then is placed on a cup 12 fabricated on a second machine in accordance with the process described above (FIG. 8); the assembly with the cup 12 is effected on the machine for the fabrication of this cup by an operation similar to encasing, by bending back in edge 12a (FIG. 9).

The invention is not limited to the cases of application which have just been described and without departing from its scope it is possible to make certain modifications with a view to its application to numerous fabrications.

Among the various advantages of the process, there can be cited the abolition of certain machines and transfer pliers as well as the increase in yield.

We claim:

1. A process for the fabrication of metal products by stamping out blanks made in a strip of metal and final forming, the process comprising the steps of stamping out a rough-shaping in the form of a cup, separating the rough-shaping from the strip, re-introducing the rough-shaping into the space which it occupied in the strip so that the rough-shaping is held by the strip, executing the final forming operations on the rough-shaping thus held by the strip, and expelling the finished product.

2. A process as claimed in claim 1 in which the rough-shaping is separated by the action of a die which introduces the rough-shaping into a guide element against the action of a sliding support.

3. A process as claimed in claim 2, in which the rough-shaping separated from the strip is re-introduced into the strip by the action of the sliding support, which is submitted to the permanent thrust of a spring, as soon as the separation die is retracted.

4. A process as claimed in claim 3, in which the rough-shaping re-introduced into the strip is submitted to a localised expansion operation by the action of a die with a projection comprising several parts.

5. A process as claimed in claim 3, in which complementary pieces are lodged in the respective rough-shapings re-introduced into the strip, and assembly is completed by an encasement step.
